UNITED STATES PATENT OFFICE.

ABIJAH SMITH, OF KINGSTON, NEW YORK.

MACHINE FOR DRESSING STONE.

Specification of Letters Patent No. 30,504, dated October 23, 1860.

To all whom it may concern:

Be it known that I, ABIJAH SMITH, of Kingston, in the county of Ulster and State of New York, have invented a new and useful Improvement in Machines for Planing, Sawing, Rubbing, and Polishing Stone, Marble, Glass, and other Materials; and I do hereby declare that the following is a full, clear, and exact description of the construction and operation of the same, reference being had to the annexed drawings, making a part of this specification, in which—

Figure 1 is a plan or top view of the machine. Figs. 2 and 3, are views of the planers or rubbers which I use in connection therewith. Fig. 4 is a saw. Figs. 5, 6, and 7 are blocks or frames to which saws are to be attached when bent for the purpose of cutting circular lines. Fig. 8, is a section of my planers when used on a circular bed, stationary or movable. Fig. 9, is a series of such sections, which when in sufficient number will form a perfect circular bed which may be used either stationary and have the stone dragged over it, or may be secured to a revolving bed, such as is commonly used for rubbing stone etc., and which form a part of the machine herein described.

30 In constructing the various parts of Fig. 1, take two pieces of timber, four by six inches and thirty or forty feet long, more or less, and secure them about thirteen to twenty feet apart and parallel to each other. 35 The upper surface of these timbers Y, Z, should be about one foot from the floor, more or less, according to the work to be performed, which arrangement may be accomplished by putting short pieces of timber under each end, and as many similar pieces of timber at intermediate points as may be found necessary to give permanency and secure them in their relative positions.

40 Across these timbers Y, Z, Fig. 1, a shaft W is laid, having proper bearings thereon at a, b. At one end of this shaft W, a crank is attached, from which a rod c, connects with a beam A consisting of a piece of hard wood of sufficient length to reach across from timber Z, Fig. 1, over and beyond timber Y, which beam A, being secured at or near one end to the timber Z, by means of a pivot or pin, at the point f, Fig. 1, which serves as a fulcrum, when the beam is caused to move

with a vibratory motion, by the connecting rod c Fig. 1, when the shaft W is set in motion, for the crank K, Fig. 1, will push forward the vibratory beam A until the crank is in an opposite position, when it will gradually draw the beam A back to its former position, and so on alternately, so long as the crank shaft W revolves.

By means of a connecting rod d attached to the beams A and B Fig. 1, (which beam B must be secured near one end to the timber Z, with a pin or pivot at f, similar to the manner in which beam A is secured) a like vibratory motion will be given to beam B, and by means of another connecting rod e Fig. 1, attached to the beams B and C, a like vibratory motion will be given to the said beam C, secured at the point f to the timber Z in the same manner that the beams A and B are secured, that is by means of a pivot or pin. To these vibratory beams A, B, C, Fig. 1 may be attached as many rubber-beams as the work to be performed may require or permit. The rubber-beam D Fig. 1, is attached to the vibratory beam A at the point g by means of a pivot or pin passing through each in such a manner that a free motion is permitted, at the other end of this rubber-beam D, a rubber is attached, in such a manner as to secure it firmly to the beam D; a rod F Fig. 1, of proper length, connects the rubber-beam D, to the lever E, at the point i by being bent at each end so as to enter the holes prepared for their reception at the points i and j Fig. 1.

The use of the rod F, Fig. 1, is to keep the rubber-beam D parallel to the timber Z and the rubber H at such a distance from the same as will cause its action to be upon any part of the surface required to be acted upon and which may be varied at pleasure by means of the lever E, which will cause the rubber H, to change its position upon the surface being rubbed, and also permit any part of the surface of the stone M to be acted upon that may be required, thereby avoiding the necessity of making the face of the rubber H as wide as the surface acted upon, and at the same time avoid action upon any part of the surface not requiring such action.

To the vibratory beam A may be attached as many rubber-beams as may be desired and the room will permit, as shown at n, o, p, Fig. 1, with the necessary connecting rods

q, r, s, to keep up a proper position of the rubber-beams, and keep them always parallel to the timber *Z*.

It will be seen that the nearer the point 5 of attachment of the rubber-beams is to the point *f*, the shorter will be the stroke or line of motion described by the rubber, and the farther the point of attachment is from the point *f* the longer will be the line of 10 motion described by the rubber, *q, r*, and *s* being attached at one end of stationary points in the timber *Z* the rubbers will in consequence move over the same parts of the stone continually.

15 The vibratory beams *A, B* and *C* in Fig. 1, I make of hard wood, two inches thick and six inches wide and of sufficient length to extend from timber *Z* over and across timber *Y*, on which timber they slide back 20 and forth. They must be perforated near one end for the reception of the pin that attaches them to the timber *Z* at the points *f, f, f*, respectively, and the beams *A, B* and *C* must also be perforated at such points as 25 may be necessary for the attachment of the rubber-beams in number, as many as may be required.

The rubbers which I use, and to which allusion has been made, are constructed in 30 such a manner as to allow the sand and water to pass to the surface to be acted upon, and consist of a series of alternate bars of metal, *b, b, b, b, b, b, b, b, b*, Figs. 2 and 3, one inch wide more or less, and the intermediate spaces, indicated by the dots and marked *a, a, a, a, a, a, a, a, a, a*, half an inch wide, more or less, into which spaces a suitable quantity of sand and water must be permitted to pass while in motion. These 35 bars *b, b, b, b, b, b, b, b, b*, may run directly across the face of the rubber, at right angles to the sides, as in Fig. 2, or at any desired angle, as in Fig. 3. The number of these bars and intermediate spaces in each rubber 40 will depend upon the length of the rubber required. I use them ordinarily for the common run of work about thirty or forty inches in length and fifteen to twenty inches in width, but for very long surfaces they 45 will require to be proportionately longer and as the rubber cuts constantly where it touches, while in motion, it must be proportioned to the length of the surface to be acted upon, and the length of the stroke given to it by 50 the rubber-beam *D* Fig. 1. If the rubber is less than the length of the surface rubbed there is a liability of a portion of that 55 surface being constantly under the cutting operation of the rubber and another portion 60 of the same surface being comparatively less under its action during each stroke, and consequently an inequality of reduction of the whole surface by the rubber. The rubber therefore must be made short and 65 have a long sweep or they must be equal to

the surface acted upon, and the sweep combined; these results can be changed at pleasure by a corresponding change in the point of connection of the vibratory beam *A* and the rubber-beam *D*, Fig. 1, as before described.

For sawing stone or marble, I use a strip of iron or other metal varying in length according to the width of the stone to be sawed. These strips of iron, Fig. 4, are 70 about four inches wide, more or less and serrated or toothed on the cutting edge. These teeth *a, a, a, a, a, a, a, a, a, a, a, a*, Fig. 4, are about an inch and the spaces notched out about half an inch, more or less. When 80 in action the saw must be fed with sand and water in proper quantities. The spaces between the teeth *a*, are thereby kept full of sand, which accelerates the cutting, with but little if any increase of power. These 85 saws should be as thin as practicable on account of the waste, which valuable material suffers from a wide saw kerf, at the same time it must be of sufficient thickness to insure strength enough. These saws must 90 be secured in a suitable frame, and when designed to cut curved lines, must be bent to the desired curve, and be attached to a block or frame Figs. 5, 6, 7, having the proper curve on their face, and these are to 95 be attached to the vibratory beam *C*, Fig. 1, at such a point *b*, as will make the radius of the line of motion correspond to the radius of the curve to which the saw is bent.

The vertical shaft *X*, Fig. 1 is designed 100 to carry a cutter on its lower end for the purpose of forming circular grooves, rosettes etc. The cutters may be made of cast iron of such form as will give the pattern designed; grooved on the face, as indicated in Fig. 10, by the dotted lines, across the face, which grooves must be deeper than the lowest indentation of the pattern. These 105 indentations are to carry sand and water necessary to cause the abrasion of the surface and produce the figure corresponding to the pattern, which sand and water are to be supplied through holes extending from the top to the grooves before named.

On the upper end of the vertical shaft *X* 115 Fig. 1, a crank may be attached, which may be used when a greater sweep is required than is available from the crank *K* on the shaft *W*, Fig. 1, which crank may be varied, by using a movable pin and placing it at 120 a greater or less distance from the center, as indicated by the dots.

The frame *N*, Fig. 1, is designed to carry one or more saws for cutting indentations, or for carrying tools for cutting molding, 125 which tools may be made of cast iron and grooved and pierced in manner like those described for the cutting circular indentations, also for sawing blocks into slabs, or slabs into pieces of any particular length. 130

In the application of my rubbers and polishers to the useful arts, a great variety of patterns may be produced, and the machine is applicable not only to ordinary free stone, 5 marble, blue and grey flagstone, but also to abrading and polishing glass and other substances where friction by rubbing is required.

For the purpose of reducing the expense 10 of rubbing and polishing large surfaces, columns, etc., of marble, stone, or other material, my machine offers an efficient substitute for hand labor, not only in the act of polishing but also in making indentations 15 cutting moldings, beads, and other regular devices thereon.

Having thus fully described my invention, what I claim as new, and desire to secure by Letters Patent, is—

The combination of vibratory beams A, 20 B, C, connecting rods c, d, e, crank K of the shaft, W, lever E, having the stay rods attached thereto, and the serrated iron tool, and rubbers, these several parts being constructed and arranged for operation, in the 25 manner described for the purposes specified.

Washington, October 5th, 1860.

ABIJAH SMITH.
